Attorney.

UNITED STATES PATENT OFFICE.

ELMER WHITE, OF TOLEDO, OHIO.

MEANS FOR INSERTING MOVABLE TYPE IN STEREOTYPE-PLATES.

SPECIFICATION forming part of Letters Patent No. 424,085, dated March 25, 1890.

Application filed May 17, 1888. Serial No. 274,210. (No model.)

To all whom it may concern.

Be it known that I, ELMER WHITE, a citizen of the United States, residing at Toledo, in the county of Lucas and State of Ohio, have 5 invented certain new and useful Improvements in Means for Inserting Movable Type in Stereotype-Plates; and I do hereby declare that the following is a full, clear, and exact description of the invention, which will enable others skilled in the art to which it 10 pertains to make and use the same, reference being had to the accompanying drawings, and to the letters of reference marked thereon, which form part of this specification.

15 My invention has relation to means for facilitating the operation of making ready the forms and plates of newspapers. In daily-newspaper offices it is essential that the forms be left open to the latest possible moment for 20 the insertion of news-matter; but where the forms are to be stereotyped all matter must be in type in time to allow for stereotyping, which usually takes from fifteen to twenty minutes, thereby frequently preventing the 25 insertion of news-items that should properly belong to the edition.

The object of my invention is to provide means whereby the stereotyping process may be proceeded with and the plate prepared at 30 the proper time with a provision for the insertion of such supplemental news-matter as may have been collected during the interim of stereotyping by means of insertible type-receptacles which shall contain the matter 35 duly set up with type, after which the receptacles are secured in the proper position within the plates previous to locking the form, by which means the latest news may be furnished in the edition to be printed.

40 The invention consists in forming the stereotype-plate with tops or openings in the columns of the same adapted to receive a type-receptacle of any desired size or form, and which shall contain the supplemental reading- 45 matter made up with type.

In the drawings, Figures 1 and 2 are perspective and side views, respectively, of a type-receptacle, Fig. 3 being a cross-sectional elevation of the same on lines $z z$, Fig. 2, the 50 receptacle being rectangular in cross-section.

Figs. 4, 5, and 6 are like views, respectively,

of a modified form, the receptacle being inclined from the base to the upper side, Fig. 6 being a section on lines $y y$, Fig. 5. Fig. 7 represents a section of a stereotype-plate 55 formed with openings for the reception of the type-receptacles. Fig. 8 is a like view showing the receptacles in place. Fig. 9 represents a section of stereotype-plate with a type-receptacle secured within the inner surface 60 of the plate.

A designates the type receptacle or holder; B, the type secured therein and locked in position by screw C; or, if desired, a spring or wedge may be employed for this purpose. 65 The receptacles or holders may be rectangular in cross-section, as shown in Figs. 1, 2, and 3, in which the sides A' are vertical, or the sides may be inclined, as shown at A'', Figs. 4 and 6.

7c
D represents the stereotype-plate, formed in the usual manner and having openings D', adapted to receive the type-holders. These openings are formed by inserting a core in the matrix previous to casting the 75 plate, that shall occupy the position intended for the type-holders. The openings may be formed in any desired location in the plate, either centrally of the surface, as shown in Fig. 9, or opening at the ends, as shown in 80 Fig. 8, and is shaped to correspond with the form of the type-receptacle. On the right of Figs. 7 and 8 are illustrated openings with vertical sides D' and limiting projections E, against which the upper edges of the holder 85 rest, while at the right of said figures the sides D'' incline from the bottom to the top of the plate, and the holder is formed to fit within the inclined sides, impinging sufficiently to allow the type to exactly register with the 90 printing-surface of the stereotype-plate.

In operation in preparing the form for stereotyping the desired number and size of spaces are reserved that are deemed sufficient to contain the supplemental matter to be inserted by means of the type-holders. The matrix is prepared in the usual way, there being cores inserted in the positions indicated in the forms, and the stereotype-plates are prepared in the usual manner.

100
During the preparation of the plate the later news-items are set up in the receptacles

Type-holders, and just prior to going to press are inserted in the opening in the plate, by which means the very latest matter may be inserted in the edition being printed.

5 Having described my invention, what I claim, and desire to secure by Letters Patent, is—

10 1. The combination, with a stereotype-plate having recesses formed therein, said recesses having vertical sides D' and limiting projections E formed thereon, of type-holders A, rectangular in cross-section, inserted within the recesses, the upper edges of the holders bearing against the limiting projections, substantially as and for the purpose described.

2. In combination with a stereotype-plate having an undercut recess, a holder carrying movable type and having an exterior contour corresponding in shape to the shape of the recess, the body of the movable type being of 20 the width of the top of the recess, as and for the purpose set forth.

In testimony that I claim the foregoing as my own I hereby affix my signature in presence of two witnesses.

ELMER WHITE.
